BABY BOTTLE

Hollister A. Thornton, P.O. Box 326,
Greensboro, Ga. 30642

Filed Feb. 18, 1971, Ser. No. 116,745

Term of patent 14 years

Int. Cl. D24—04

U.S. Cl. D83—8 A

FIG. 1 is a perspective view of the baby bottle showing my new design;

FIG. 2 is a side elevational view of the baby bottle;

FIG. 3 is a bottom plan view of the baby bottle;

FIG. 4 is a front elevational view of the baby bottle; and

FIG. 5 is a rear elevational view of the baby bottle.

The characteristic feature of my design resides in the specific configuration of the groove element as best illustrated in FIGS. 2 and 5 on the drawing.

I claim:

The ornamental design for a baby bottle, as shown and described.
